Specification for Design.

Patented Aug. 24, 1920.

Application filed March 17, 1920. Serial No. 366,710. Term of patent 7 years.

To all whom it may concern:

Be it known that I, LEWIS F. STAFFORD, a citizen of the United States, residing at Chicago, in the county of Cook and State of Illinois, have invented a new, original, and ornamental Design for an Automobile-Bumper, as shown in the accompanying drawing.

In the drawings:

Figure 1 is a perspective of my design, and

Fig. 2 is a top plan thereof.

What I claim is:

The ornamental design for an automobile bumper, as shown.

In testimony whereof I have hereunto set my hand at Chicago, Illinois, this 23d day of February, 1920.

LEWIS F. STAFFORD.
